US0D1070180S

(12) **United States Design Patent** (10) **Patent No.:** **US D1,070,180 S**
(45) **Date of Patent:** **** Apr. 8, 2025**

(54) **MIRROR**

(71) Applicant: **Yizhi Deng**, Hunan (CN)

(72) Inventor: **Yizhi Deng**, Hunan (CN)

(**) Term: **15 Years**

(21) Appl. No.: **29/951,115**

(22) Filed: **Jul. 8, 2024**

(30) **Foreign Application Priority Data**

Jun. 14, 2024 (CN) 202430366442.2

(51) **LOC (15) Cl.** **28-03**

(52) **U.S. Cl.**

USPC **D28/64.1; D28/83**

(58) **Field of Classification Search**

USPC D28/4, 9, 58, 61, 62, 64.1, 64.2, 64.3, D28/64.4, 64.5, 64.6, 64.7, 73, 76, 77, 78, D28/79, 80, 81, 82, 83, 84, 99; 206/216, 206/542, 581; D6/300, 321, 664.1, 568; 132/286, 291, 296, 301, 304, 309, 316, 132/333

CPC A45D 42/00; A45D 42/02; A45D 42/04; A45D 42/06; A45D 42/08; A45D 42/10; A45D 42/12; A45D 42/16; A45D 42/18; A45D 42/22; A45D 42/24; A45D 33/008; A45D 33/00; A45D 2200/00; A45D 2200/25

See application file for complete search history.

(57) **CLAIM**

The ornamental design for a mirror as shown and described.

DESCRIPTION

FIG. 1 is a perspective view of a mirror showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the mirror in a closed position, showing my new design.

The dash-dash broken lines in the drawings depict portions of the mirror that form no part of the claimed design.

1 Claim, 9 Drawing Sheets
